GEORGE HOOVER AND ARTEMUS N. HADLEY, OF RICHMOND, INDIANA.

Letters Patent No. 69,211, dated September 24, 1867.

IMPROVEMENT IN SPINNING MACHINE.

The Schedule referred to in these Letters Patent and making part of the same.

TO WHOM IT MAY CONCERN:

Be it known that we, GEORGE HOOVER and ARTEMUS N. HADLEY, both of Richmond, Wayne county, Indiana, have invented a new and useful Hand-Spinning Machine; and we hereby declare the following to be a full, clear, and exact description thereof, reference being had to the accompanying drawings, making part of this specification.

This is an improvement in the class of hand-spinning machines adapted for the simultaneous manufacture of a number of threads or yarns, and our invention comprises a provision for preserving a uniform pressure of doffer-roller, with varying lengths and diameters of roving-spoils; a provision whereby the act of depressing the clove-sash becomes effectual for the automatic delivery of the quantum of roving required for the ensuing stretch or draw; a provision whereby such automatic delivery is made adjustable in quantity in inverse ratio to the desired draught; an automatic provision whereby the opening of the clove becomes effective to nip the roving-delivery cord and the closure of the clove to liberate said cord; a form of clove-jaws, adapted to securely nip the roving preparatory to drawing and twisting; an adjustable and automatic provision whereby the faller-fly is alternately released and retracted by the descent and ascent of the clove-sash; an arrangement of spindle-driving belt, whorls, and pressure pulleys, whereby an indefinite number of pulleys may be operated by a single belt; provisions for doubling and twisting in a hand-spinning machine; a provision for reeling, &c.

Figure 1 is a perspective view of a machine embodying our improvements, the sash having commenced its descent with its clove open, and the roving-delivery cord nipped. A portion of the top rail is, in this figure, shown broken away, so as to expose the spindles.

Figure 2 is a transverse section of the machine, with end views of the driving and counter-shafts.

The operative parts of our machine are supported in a frame, A, rectangular in its horizontal section, and somewhat high and broad for its width from front to back. The back of this frame may be vertical. Its front portion we prefer to lean slightly rearward, as shown. A front rail, B, and back rail, B', are crossed rectangularly by two rails, C C', so attached to said rails B B' as to be capable of being set nearer together or further apart, and are provided near their rear ends with two bearings, D D', for the journals of a roving-delivery cylinder, E. These bearings, being slotted, are capable of approachment or separation, so as to admit cylinders of different lengths adapted to work with roving-spoils of the diverse lengths and diameters employed by different carders. The cylinder E is scored e, circumferentially, to receive and be operated by the roving-delivery cord F. Attached adjustably to the rails C C' are two inclined arms, G G', which, in conjunction, with the cylinder E, form bearings for the roving-spool H, whose gudgeons, h h', and periphery rest respectively upon said arms and the periphery of said cylinder. The arms G G' should be set at such an inclination as to support the doffing-roller I on the peripheries of the roving-spool H and delivery-cylinder E, as near the top of the latter as is practicable without rolling off. Extending from the bottom front rail B to the top front rail B'', and parallel with the slightly inclined front posts J J' of the frame, are two rods, K K', which serve as guides to the clove-sash L M, whose front jaw, L, is provided with loops N enclosing said guides. Projecting rearward from the jaw L are two brackets, O, to which the rear jaw M is hinged by means of pivots P. Projecting downward and rearward from the jaw L are eyelets, Q, which correspond in number to the spindles, and which serve to properly conduct the rovings or yarns thereto. The jaw L is, about its mid-width, excavated to receive and hold an India-rubber pad, R, which pad is traversed by the stem s of a loop, S, which receives the roving-delivery cord F, and whose stem s aforesaid, being attached to the rear or movable jaw M, is drawn backward by the act of opening of said jaw, so as, at the proper moment, to automatically nip the cord F between said loop S and pad R, and thereby to cause the sash, in descending, to rotate the roving-delivery cylinder, so as to give out the proper quantum of roving for the ensuing draw. Extending upward and rearward from the jaw L is a curved finger, T, which, as the sash approaches the top of its stroke, operates to retract the faller-wire, in the manner presently explained. Extending upward and forward from the jaw L is a handle, U, by which to elevate and depress the sash. A spiral spring, V, extending from the lower part of the jaw L to the back of the jaw M, acts to close the said jaw M tightly against the jaw L. A lip or ridge, m, on the jaw M, entering a groove, l, in the jaw L, or a series of corrugations on one jaw entering corresponding corrugations on the other jaw, enable the said jaws or clove to firmly gripe the rovings in the act of closing, and thus effectually prevent

any slip of the yarn in the operation of drawing and twisting. Each bracket, O, has, concentric with its pivot P, a groove, o, having a jog or notch, o'. This groove o receives a tongue, W, which is pivoted to and projects from the jaw M. Depending from the frame is a tappet, X, which, arresting the ascent of the tongue W as the sash nears the top of its stroke, forces the jaw M open and the tongue into the jog o', which jog holds it and the jaw to said open position until released by the descent of the sash, bringing the tongue W in contact with a releasing or gauge-pin, X', projecting from the frame, whereupon the jaw M, being liberated, springs shut, and nips the rovings, releasing at the same instant the cord F, as before stated, so as to stop for the time being the delivery of the roving. A series of holes, a, provided in the frame, enable the pin X' to be shifted up or down, so as to nip the roving and to release the delivery-cord, earlier or later, in the downward stroke of the sash, according to the desired draught, thus adapting the machine for drawing and twisting either common rolls or roving to any desired fineness or density, at the discretion of the operator, or for merely doubling and twisting yarn already spun. The spindles Y are journalled equidistantly in the top of the frame, with their points projecting forward, and slightly downward, and reaching nearly vertically over the centre of the clove. The entire series of spindle-whorls y are rotated simultaneously by means of a round belt, Z, extending along their tops, and around the larger member 1 of a differential pulley, 1 2, which revolves on a stationary counter-shaft or stud, 25, and is driven by a belt, 3, extended from the driving-pulley 4 around the smaller member 2. The necessary impact and traction of the belt Z upon the whorls y is obtained by the interposition of a suitable number of pressure-pulleys or idlers, 5, having their nadirs sufficiently below the zeniths of the whorls to accomplish that purpose. Provision for a slight vertical adjustment of the pressure-pulleys 5 may be made by slotting their bearings, and the application of a thumb-screw, 5'; but this adjustment once made is seldom required to be altered, and therefore to enable the belt to be readily strained or slackened without disturbing the pressure-pulleys, the shaft 25 is made to occupy a slot, 26, in the frame, and being shifted up or down therein at discretion of the operator, is secured to any specific adjustment by means of a nut, 27. This provision also facilitates the crossing of the belt Z for doubling and twisting, as hereafter explained. The faller-wire 6 projects from a shaft, 7, journalled in the frame, and is caused to automatically assume a position near the heels of the spindles by the stress of a spring, 8, attached to the end of an arm, 7*, which is so applied as to exert the greatest leverage on the shaft 7 when the wire is in said depressed position. The spring 8 terminates in a series of links, 9, either one of which being engaged over a hook, 10, on the frame, the automatic depression of the faller-wire is made to take place with any desired force. Depending rigidly from the faller-wire shaft is a spur, 11, which, when the said wire has been fully lifted or retracted by the ascent of the curved finger T, before spoken of, engages on a shoulder, 12, of a bent spring, 13, attached to the frame, and thus locks or detains the faller-wire to its upper position. The unlocking of the faller-wire is effected by the impingement of the bracket O, as the sash commences to ascend, against a trigger, 14, connected by a wire, 15, to a bell-crank, 16, which, slightly retracting the bent spring 13, disengages the spur 11 therefrom, and releases the faller-wire.

The spindles may be run naked, after the manner of mule spinning, but we prefer to use bobbins, which, when filled, may be slipped off of the spindles with their cops or broaches entire, or their contents may be drawn off on to our reel, as will presently appear. The roving-delivery cord F is made continuous by means of hook and eye f, and being rove through the loop S is carried upward over a pulley, 17, attached to the front top rail by a bearing, which may be adjustable if desired, thence downward around a pulley, 18, whose bearing, 19, is slotted, and fixable by a screw, 20, out or in for the proper tension of the cord. From the pulley 18 the cord is passed around the groove e in the roving-delivery cylinder E, whence it returns again around the pulley 18. The sash L M is suspended by a cord, 21, which, being carried over pulleys 22 and 23 hung in the top of the frame, terminates in a counterbalance, 24. The shaft 28 of the drive-pulley 4 journals, by its rear end, in a swivelled box, 29, and by its fore end in an open box, 30, to which it is retained when desired by means of a hook, 31. The said shaft terminates in front in a winch or crank, 38, which is, in conjunction with the handle of the sash, the prime mover of the entire drawing, spinning, and twisting operations. Projecting rectangularly from the front of the driving-pulley 4 is a series of pins or rundles, 32, which, in conjunction with said pulley, constitute a reel employed in connection with the doubling and twisting arrangement, hereafter described, to wind off the worsted from the bobbins. A full hank having thus been wound off, can be readily removed from the reel upon temporarily lifting from its open bearing the crank end of the shaft 28. In order to be enabled to double and twist in the same machine, we provide, in rear of the roving-cylinders, a series of studs, 33, carrying bobbins 34, two or more to each upper spindle, and as many eyelets, 35, (of which only a portion are shown in drawing,) depending from a suitable rathe, 36, in rear of the frame. The object of these eyelets is to keep every individual thread apart from all the others and under proper tension, so as to prevent kinks and entanglement on their way to the eyelets Q. For doubling and twisting, we shift the gauge-pin X' to an orifice, 37, near the bottom of the frame, because for this purpose, no drawing being needed, the clove is required to remain open during the entire descent of the sash.

To spin the rovings or continuous rolls, such as are used in factories, take the spool filled with rovings and place it with its gudgeons resting on the inclined bearing-arms, and with its periphery resting on that of the delivering cylinder, so that as the rovings are spun off, the spool may gradually settle down on the cylinder. Then taking up the ends of the rovings, run off a sufficient quantity to reach up through the sash to the points of the spindles or bobbins. Grasping then the handle of the sash, elevate the latter to the top of the frame, then bring the rovings through the eyelets at the bottom of the sash, and through the jaws of the same, being careful that all of the rovings are drawn up with equal tension from the spool below. The small roller or doffer may now be placed in the gorge of the roving-spool and delivery-cylinder, the inclined arms being raised or lowered so as to bring the doffer as nearly as possible vertically over the cylinder. Then put the bobbins on

the spindles, shoving them as far back as possible, except that a sufficient space must be left between the bobbin and the frame to permit an unrestricted rotation of the spindles, and drawing the ends of the rovings under the now elevated faller-wire secure them to their respective bobbins.

To make coarse yarn, move the gauge-pin down; to make fine yarn, move said pin up. The rovings being securely attached to the bobbins, the yet open sash is to be depressed, letting the rovings pass through the open jaws, until the sash strikes the gauge-pin X' on the upright, which action operates to release the cord F and to stop the delivery of roving from the spool, and simultaneously therewith to nip all the rovings at an equal distance below the spindles. The operator now, with his right hand upon the winch or crank, twists a little in order to strengthen the rovings before continuing the downward motion of the sash, and then, while still revolving the winch, resumes said downward motion with gradually decreasing velocity, until the sash strikes the bottom rail, and then continues to twist until the yarn has attained the desired density. He then reverses the crank sufficiently to clear the yarn from the points of the bobbins. He then commences to elevate the sash with his left hand, keeping hold of the crank with his right hand until the sash strikes the trigger and relieves the faller-wire. He then, continuing to elevate the sash with his left hand, slowly turns the crank forward with his right, and the yarn will be wound around the bobbins to form a broach or cop. On approaching the termination of its upward stroke, the curved finger on the top of the sash elevates the faller-wire, which, on its part, draws the yarn out to the end of the bobbin, and, becoming locked in the spring-catch or detent 13, sets the machine ready for the next draw.

To spin short rolls, such as are commonly used on the old spinning-wheels, the roving-delivery cord may be unhooked and removed from the machine, and the rolls be spliced below the sash as fast as they are spun up, and in most cases the gauge-pin should be shifted further up to secure the required draught.

To double and twist, fill two entire sets of bobbins, and remove the same from the spindles above to the studs below, and conducting the end of each yarv through its proper eyelet in the rathe, bring the said yarns in pairs through their appropriate eyelets of sash, and through the jaws of the latter, and fasten each pair to its proper spindle, then cross the belt Z, so as to give the spindles a reverse rotation, and shift the gauge-pin X' to the bottom hole 37, and operate the same as in spinning. For "tripling," combine three yarns in the same way. For reeling, detach the belts 3 and F, attach the end of the yarn or thread from one or more spindles or bobbins to one of the rundles, 32, and turn the crank until a hank of the desired size is wound off. Then slip the hank off of the rundles and let it hang on the main shaft 28, push back the hook 31, elevate the front end of the said shaft clear of its bearing, and remove the hank.

We claim herein as new, and of our invention—

1. The adjustable inclined bearing-arras G G', for use with roving-spools of diverse lengths and diameters, in the described combination with the roving-delivery cylinder E and gravitating doffer-roller I.

2. In the described combination, the roving-delivery cylinder E, the automatically opening and closing clove-sash, and the roving-delivery belt or cord F, having permanent connection with said cylinder, and intermittent connection with said sash, substantially as and for the purposes set forth.

3. The roving-cord clasp S, combined in one sash with the clove, and being closed and opened by the opposite actions of the latter, whereby an amount of roving is automatically delivered exactly corresponding to that required for the ensuing stretch, whether the same be more or less.

4. The loop or cord-clasp S, whose stem, s, is drawn through the friction-pad R, and operated by the movable jaw M of the clove, in manner substantially as set forth.

5. The arrangement of vertically-guided and balanced clove-sash, whose movable and self-closing jaw M has a tongue, W, which, impinging against a tappet, X, is made to engage behind a notch, o, or devices substantially equivalent, in the described combination with an adjustable releasing-pin, X', for the automatic opening and closure of the clove, for any desired length or stretch of roving, as set forth.

6. The provision, on a vertically-balanced and reciprocating clove-sash, of the rearwardly and upwardly curved finger T, for retraction of the faller-wire, in the manner explained.

7. In the described combination, the vibrating faller-wire 6, adjustable retracting spring 8, spur 11, spring detent 13, and releasing mechanism 14, 15, 16, whereby said faller-wire is automatically operated by the ascent and descent of the clove-sash, in the manner explained.

8. The spiral spring 8 and arm 7*, applied so as to impart a downward movement to the faller-wire, and adapted to exert the greatest leverage when the faller-wire is in its depressed position, as described.

9. The arrangement of the adjustable driving-pulley 1, band Z, spindles Y, whorls y, and intermediate pressure-pulleys or rollers 5, as and for the purpose herein described.

10. The provision, in the plane of the spindles, of the driving-pulley 4, armed with rundles 32, and journaled at rear in the swivelled bearing 29, and at front in the open bearing 30, for convenient winding off and removal of the hanks, in the manner explained.

In testimony of which invention we hereunto set our hands.

GEORGE HOOVER,
ARTEMUS N. HADLEY.
